UNITED STATES PATENT OFFICE.

EDWARD MOLLOY, OF CLAPHAM COMMON, LONDON, ENGLAND, ASSIGNOR TO CYRIL FELLS STACEY, OF LONDON, ENGLAND.

SUBMERSIBLE TOY.

1,396,650.

Specification of Letters Patent. Patented Nov. 8, 1921.

Application filed April 6, 1921. Serial No. 458,971.

To all whom it may concern:

Be it known that I, EDWARD MOLLOY, a subject of the King of England, residing at Clapham Common, London, England, have 5 invented certain new and useful Improvements in Submersible Toys, (for which I have filed application in Great Britain Jan. 20, 1920, No. 1775/20), of which the following is a specification.

10 This invention relates to submersible toys and has for one of its objects to provide a cheap and easily constructed toy submarine or the like which, when set for diving and placed free on the water, will first without 15 further external manipulation submerge and subsequently rise again to the surface. Accordingly, the invention comprises a hull, shell, or other part forming the body of the toy provided with means which after being 20 set for operation, automatically cause a part to change in shape so as to vary the effective displacement of the toy without further human actuation of the latter. Preferably the rising of the toy to the surface is arranged 25 to take place at a considerable, or at any rate an appreciable, time after submersion and, according to another feature of the invention, this is effected by arranging the said 30 means to comprise a rubber or like collapsible part which is first deformed and then 35 is permitted slowly to return to its normal shape by causing air or water in proximity to the said part to flow through a restricted passage. In a preferred form, the variation 40 in displacement is regulated by the percolation of the fluid through a chalk or like plug. The toy may be provided with propelling means, such as a spring-controlled flap or flaps, which are automatically permitted 45 to operate through the variation in displacement of the toy. Other features of the invention will appear from the following description, reference being made to the accompanying drawings of two embodiments 50 of the invention as applied to a toy submarine. It is, however, to be understood that the invention may be variously arranged and applied to other submersible toys without departing from its spirit and scope.

In the drawings:—

Figure 1 is a side elevation of one embodiment of the invention as applied to a toy submarine;

Fig. 2 is a plan of the same; 55

Fig. 3 is a front elevation;

Fig. 4 is a sectional elevation on the line 4—4 in Fig. 1;

Fig. 5 is a rear elevation;

Fig. 6 is an inverted sectional plan on 60 the line 6—6 in Fig. 1;

Figs. 7—10 are detail views referred to later;

Fig. 11 is a side elevation of a second embodiment of the invention also as applied 65 to a toy submarine;

Fig. 12 is a plan thereof;

Fig. 13 is a vertical sectional elevation on the line 13—13 in Fig. 11;

Fig. 14 is a detail view referred to later, 70 and

Fig. 15 is a vertical section on the line 15—15 in Fig. 11, omitting the bulb and the periscope.

Like reference characters indicate like 75 parts throughout the drawings.

Referring to the construction shown in Figs. 1—10, the submarine hull is made of tin-plate, and is of uniform section except at the bow and stern. As illustrated in 80 Figs. 3—5, such section is octagonal, the faces of the octagon being designated 2, 3, 5, 7, 8, 9, 11, 12 (Fig. 4). The upper face 5 has secured to it an inverted channel 14 bent up from a sheet of tin-plate so as to form a 85 narrow deck having a pointed end 15 toward the stern and supporting the conning tower 16. The upper middle section and stern of the hull are cut from one piece of tin-plate as shown in Fig. 10, the faces 2, 3, 90 5, 7 and 8 being indicated in that figure. It will be seen that the stern end of that piece is shaped so that when the piece is bent up, the faces 2 and 8 are extended and curved inward (Figs. 2 and 5) to meet at 95 the stern. The two faces 3 and 7 are cut at their stern ends to a curved taper as shown at 17 and 18 (Fig. 10) so that these tapered ends can be bent inward and downward as illustrated in Figs. 1, 2 and 5, to meet the 100 faces 2, 8 and 5, the face 5 being prolonged at 19 and bent downward to join the top edges of the faces 2 and 8. The meeting edges are joined together in any suitable manner. The faces 9, 11 and 12 are cut 105 from one piece of tin-plate terminating at its forward end at the line 21, and at its rear end at the line 22 (Figs. 1 and 2), thus

leaving at the stern an opening 23 (Fig. 5) by which water can easily gain access to the inside of the hull when the boat is placed on the water. The bow is formed from one piece of tin-plate cut out to the outline shown in Fig. 9 and bent up to the shape shown in Figs. 1, 2 and 3, the various panels 24-33 having the same reference numbers in all these figures.

10 It will be seen that by cutting V-shaped parts 34 out from the rear edge of the bow plate, the panels or "flats" 24, 25, 26, 30, 31, 32, 33 are made to curve or merge into the parallel faces 12, 2, 3, 5, 7, 8, 9, 11 of the central portion of the hull. The panels 27, 28 and 29 connect with the channel 14 constituting the deck. An opening 36 (Figs. 3 and 9) is made under the bow and holes 37, 38 and 39 are formed in the deck and stern to facilitate water entering the hull when the boat is placed on the water, the air in the hull then escaping by the holes 37, 38 and 39.

An air reservoir 40 is formed in the upper part of the center of the hull by soldering in a horizontal partition 41 having upturned ends 42. A diamond-shaped opening (see Fig. 6) is cut in the partition 41, the edges of the opening being indicated at 43, 44 and 45. This opening accommodates two tin-plate cones or pyramids 46 and 47 placed base to base to constitute an expansion chamber 48 in which is a rubber bulb 49 connected to the air reservoir 40 by a tube 51. The pyramids and the partition 41 are soldered to one another where their edges meet so that the air in the reservoir is confined therein but is in communication with the bulb 49. A rod 52 representing the periscope passes down through an easy-fitting hole in a horizontal deck-plate 53 of the conning tower and through a similar hole in the channel 14 (Fig. 4), also through a tube 54 (Figs. 7 and 8) passing through the reservoir. This tube is soldered into a hole 55 (Fig. 10) in the face 5 and into the pyramids 46 and 47. A button 56 on the lower end of the rod bears on the bulb 49. A rubber flap valve is provided to allow water readily to enter the chamber 48, but the water can escape only through the small clearance between the periscope rod and the tube 54. This valve consists of a piece of sheet rubber 57 secured at one end inside the pyramid 47 by a split rivet 58 so that its other end covers a hole 59 in that pyramid. A small ballast weight 50 is fixed to the underside of the hull, and is of just sufficient weight to keep the face 5 level with the surface of the water when the bulb 49 is fully expanded.

In use, the periscope rod 52 is depressed to flatten out the bulb 49, and the rod is held depressed while the submarine rests in the water, until the hull (except for the reser-

voir 40) is flooded. It will be understood that water enters the expansion chamber 48 through the flap valve 57, the air previously therein escaping between the rod 52 and the tube 54 into the channel 14, thence out by holes 37 or 38 or through the hole in the channel through which the rod passes.

The flattening of the bulb increases the air pressure in the reservoir and the tendency of the air to return to the bulb of course tends to expand the latter, but it can only do so by forcing out the water in the chamber 48. The water can only escape very slowly around the periscope through the small clearance in the tube 54.

When therefore the toy is released, it sinks because its weight is sufficient to cause this when the bulb is collapsed. The toy remains submerged while the bulb is slowly expanding and rises when expansion is nearing completion. The parts are made light enough for the conning tower and deck work to stand out of the water when the toy floats with the bulb fully expanded.

In the modified arrangement shown in Figs. 11 to 14 which is preferred because of its simple construction, the air reservoir 60 is formed by soldering in a tin plate partition bent about transverse horizontal lines 61*, 62*, 64*, 65*, 66*, 67*, 68*, to form flat faces 61 to 69. As explained in connection with the earlier construction, the faces 2, 3, 5, 7 and 8 of the upper metal section of the hollow hull are bent up out of one portion of tin plate. The faces 61 and 69 are soldered at their top edges to the face 5, and at their side edges to the faces 3 and 7, and 2 and 8. The substantially horizontal faces 62 and 68, and the substantially vertical faces 63 and 67, are soldered at their side edges to the faces 2 and 8. The inclined faces 64 and 66, and the horizontal face 65, are soldered at their side edges to the faces 3 and 7. The rubber bulb 70 is connected with a metal tube 71 (Figs. 11 and 14) soldered into a hole made in the face 67 midway between its side edges. The periscope rod 72 passes down through the tube 73 (Fig. 13) which is soldered in between the faces 5 and 65. This tube is considerably larger in diameter than the rod which has secured to its lower end the button 74.

A chalk or other porous plug 75 is sealed into the rear end of the tube 71 in the position indicated at 76. A lateral hole 77 is made in the tube 71 just in front of the position occupied by the chalk plug. The hole is covered by a thin rubber band 78 surrounding the tube 71 and in slight tension. The band thus forms a valve allowing air to escape easily out of the tube 71 into the reservoir 60 but not to return. Fig. 14 shows the plug 75 and band 78 detached from the tube 73.

In use, the periscope is pressed down to flatten out the bulb 70 and squeeze the air out of the bulb into the reservoir through the valve hole 77. The air can only get back into the bulb by percolating slowly through the chalk plug 75, consequently when the boat is placed on the water, it quickly sinks because the bulb is still collapsed. After a considerable time interval 5 (say two to five minutes, according to the length and effective diameter of the chalk plug) the bulb expands sufficiently to cause the periscope to appear above the surface 10 of the water. By the time expansion is complete, the conning tower and deck work 15 stand out of the water, as in the previous construction.

To make the boat more interesting, it may be made to propel itself forward, preferably just as it is emerging out of the water. This is effected by providing on each side 20 of the hull a pair of ears 80 carrying a pivot-pin 81 forming a hinge for a wing or flap 82, the two flaps being of similar construction. The flaps are normally held 25 pointing rearward as shown, by elastic band 83 passing above a ledge 84 on the stern and fastened to studs 85 depending from the flaps. The latter are made of tin-plate flanged at the edge, the vertical plane 30 in which the tin-plate lies being indicated at 79 in Fig. 12. A bent metal strip 86 is cranked as shown in Fig. 13 so that its middle portion passes over the button 74 and has a hole 87 through 35 which the periscope rod 72 passes loosely. The ends of the strip have notches 88 and project through vertical slots 89 in the side faces of the hull. Thus hooked ends 90 project laterally from the hull. Each flap 40 82 has cut in it a hole 91 leaving a ledge 92.

In operation, before the periscope is pressed down the flaps 82 are folded forward and held in the dotted position shown 45 in Fig. 12 the hooked ends 90 then projecting into the wide upper ends of the holes 91 in the flaps. When the periscope is forced down, the strip 86 falls until the shanks 93 of the hooked ends rest on the bottom edges 94 of the holes in the flaps. The hooked ends 90 therefore catch against the ledges 92 and retain the flaps in their 50 forward position.

When the bulb 70 is expanding and the 55 boat rising to the surface, the bulb slowly pushes up the button 74 until the latter comes up against the underside of the strip 86. The final expansion of the bulb then further pushes up the button and strip, thus 60 lifting the hooked ends 90 off the ledges 92 and permitting the elastic band 83 to swing the flaps rearward. This movement of the flaps pushes the toy forward and its momentum carries it some distance in the 65 water.

An advantage of the above construction is that, apart from the soldering in of the air reservoir 60 and tubes 71 and 73, any joints in the rest of the hull need not be watertight. Further, as the hull (except 70 for the reservoir) is flooded, quite a small ballast weight in comparison with the size of the toy suffices to cause submersion. This makes the boat light and economizes lead. The method of folding up the cut-out pieces 75 of tin-plate to form the hull obviates the need for bulging the sheet in machine presses.

What I claim as my invention and desire to secure by Letters Patent is:—

1. A submersible toy comprising in combination a casing, buoyancy-producing means carried by said casing, and means operable by human agency for overcoming the buoyancy produced thereby and thus permitting the toy to sink, said buoyancy-producing means including a member carried by the casing and, after the last named means have operated, automatically changing in size without further human actuation of the toy to vary the effective displacement of the toy and cause the toy entirely by its own automatic action to rise again.

2. A submersible toy comprising in combination a casing, buoyancy-producing means carried by said casing, and means operable by human agency for lessening at will the buoyancy produced thereby and thus permitting the toy to sink, said buoyancy-producing means including a member carried by the casing and, after the last named means have operated, automatically changing in shape without further human actuation of the toy to restore the buoyancy and cause the toy to rise again entirely by its own automatic action.

3. A submersible toy comprising in combination a casing, buoyancy-producing means carried by said casing, and means operable by human agency for discontinuing a sufficiently large proportion of the buoyancy produced thereby to permit the toy to sink, said buoyancy producing means including a member carried by the casing and, after the toy has sunk, automatically increasing in size without further human actuation of the toy to increase the effective displacement of the toy and cause the toy entirely by its own automatic action to rise again.

4. A submersible toy comprising in combination a casing, buoyancy-producing means carried by said casing and including a collapsible member, and means operable by human agency for compressing said member to lessen the buoyancy of the toy and permit it to sink, said buoyancy-producing means also including means for automatically securing the slow return of said member to its normal shape without further

human actuation of the toy to cause the toy entirely by its own automatic action to rise again.

5. A submersible toy comprising in combination a casing, an air tank carried by said casing, a collapsible member also carried by said casing and having its interior in communication with the interior of said air tank, means for compressing said member to discharge its contents into the air tank and thus permit the toy to sink, and means for restricting the rate at which the said member returns to its normal shape.

10 6. A submersible toy comprising in combination a casing, an air tank carried by said casing, a collapsible rubber chamber in communication with the interior of said air tank, means for compressing said chamber to discharge its contents into the air tank and thus permit the toy to sink, and means for restricting the rate at which air from the tank flows into said chamber to return the latter to its normal shape, said means including a restricted orifice through 20 25 which fluid controlling the chamber slowly passes.

7. A submersible toy comprising in combination a casing, an air tank carried by said casing, a collapsible member also carried by said casing and having its interior in communication with the interior of said air tank through a conduit, a porous plug fitted within said conduit, and means for compressing said collapsible member to discharge its contents into the air tank and thus permit the toy to sink, said plug restricting the rate of flow of air from the tank back into the said collapsible member.

30 40 45 50 55 8. A submersible toy comprising in combination a casing, an air tank carried by said casing, a collapsible member also carried by said casing and having its interior in communication with the interior of said air tank through a perforated conduit, a valve for the perforation in said conduit, means for controlling said valve to permit of the passage of air from the collapsible member in the air tank but to prevent passage of air in the reverse direction, a chalk plug fitted within said conduit and permitting the slow passage of air from the tank back into the collapsible member, and means for compressing the collapsible member to discharge its contents into the air tank.

55 9. A submersible toy comprising in combination a casing, buoyancy-producing means carried by said casing, means for overcoming the buoyancy produced thereby and thus permitting the toy to sink, said buoyancy-producing means including, a member carried by the casing and, after the last named means have operated, automatically changing in size to vary the effective displacement of the toy and cause the toy to rise again, and propelling means for the toy

which are automatically permitted to operate through said variation in the effective displacement of the toy.

10 70 75 80 10. A submersible toy comprising in combination a casing, buoyancy-producing means carried by said casing, means for overcoming the buoyancy produced thereby and thus permitting the toy to sink, said buoyancy-producing means including a member carried by the casing and, after the last named means have operated, automatically changing in size to vary the effective displacement of the toy and cause the toy to rise again, and propelling means for the toy operating automatically as the toy arises again.

11 85 90 95 11. A submersible toy comprising in combination a casing, buoyancy-producing means carried by said casing and including a collapsible member, means for compressing said member to lessen the buoyancy of the toy and permit it to sink, means for securing the slow return of said member to its normal shape to cause the toy to rise again, and propelling means for the toy which are brought into operation as the collapsible member approaches normal shape again.

12 95 100 105 110 115 120 125 130 12. A submersible toy comprising in combination a casing, buoyancy-producing means carried by said casing and including a collapsible member, means for compressing said member to lessen the buoyancy of the toy and permit it to sink, means for securing the slow return of said member to its normal shape to cause the toy to rise again, flaps pivoted at the exterior of said casing, means tending to partially rotate said flaps, detents for holding said flaps in position against the pull of said last named means, and means for releasing the detents as the toy rises.

13 110 115 120 125 130 13. A submersible toy comprising in combination a casing, buoyancy-producing means carried by said casing and including a collapsible member, means for compressing said member to lessen the buoyancy of the toy and permit it to sink, means for securing the slow return of said member to its normal shape to cause the toy to rise again, flaps pivoted at the exterior of said casing, means tending to partially rotate said flaps, and detents for holding said flaps in position against the pull of said last named means, said collapsible member being adapted to engage the detents and release them as the collapsible member approaches normal shape again.

14 125 130 13. A submersible toy comprising in combination a casing, an air tank carried by said casing, a collapsible member also carried by said casing and in communication with the air tank, said casing being open to the inlet of liquid in which the toy is to be submerged but the air tank and collapsible

member being closed against the inlet of such liquid, means for compressing the collapsible member to lessen the buoyancy of the toy and permit it to sink and means for 5 securing the slow return of said collapsible member to its normal shape to cause the toy to rise again.

15. A toy submarine comprising in combination a casing having a main hollow body 10 part of octagonal cross section, and a pointed bow member formed with tapering flat faces and secured to said body part, buoyancy-producing means carried by said casing, and means operable by human agency for

overcoming the buoyancy produced thereby 15 and thus permitting the toy to sink, said buoyancy-producing means including a member carried by the casing and, after the last named means have operated, automatically changing in size without further human actuation of the toy to vary the effective displacement of the toy and cause the toy entirely by its own automatic action to rise again.

In testimony whereof I affix my signature.

EDWARD MOLLOY.
